UNITED STATES PATENT OFFICE.

WILHELM WAGNER, OF MANSFELD, GERMANY.

HYDRAULIC PUMP.

SPECIFICATION forming part of Letters Patent No. 707,284, dated August 19, 1902.

Application filed February 6, 1901; Serial No. 46,180. (No model.)

To all whom it may concern:

Be it known that I, WILHELM WAGNER, a subject of the King of Prussia and Emperor of Germany, and a resident of Mansfeld, in 5 the Kingdom of Prussia and Empire of Germany, have invented certain new and useful Improvements in Hydraulic Pumps, of which the following is a specification.

This invention relates to the construction 10 of hydraulic pumps; and its object is to provide means whereby large quantities of fluid can be transmitted under high pressure by manual labor and with little power, which has the advantage of furnishing an improved 15 arrangement essentially suitable for use as a fire-pump or water-supplying medium.

In my invention the weight of a water column is utilized to assist in the operation of the pump.

20 With these ends in view my invention consists in certain features of novelty in the construction, combination, and arrangement of parts by which the said objects and certain other objects hereinafter appearing are attained, all as fully described with reference 25 to the accompanying drawings and more particularly claimed.

Figure 1 is a sectional view of my improved single-acting hydraulic pump. Fig. 2 is a 30 similar view of my double-acting hydraulic pump.

a is a fluid-column cylinder having a discharge-pipe *b*. *c* is a lower pressure-cylinder, and *d* is an upper pressure-cylinder supported 35 on the lower pressure-cylinder by a housing *e*. The lower and upper ends, respectively, of these pressure-cylinders are connected, by means of pipes *p*, with the air-chamber *f* of the fluid-column cylinder. The lower and upper cylinders are of different 40 diameters and provided with differential pistons *k* and *l*, respectively, the lower piston *k* being the working piston and the upper piston *l* the balancing-piston. Both the pistons 45 oppose the pressure of the fluid column in the lift or discharge pipe *b*. The space above the lower piston *k* is in communication with a valve-casing *s*, connected with the fluid-column cylinder and controlled by a suction- 50 valve *m* and a pressure-valve *o*. A suction-pipe *n* is connected with the valve-casing beneath the suction-valve. The area of the

two pistons *k* and *l* is calculated to suit the suction and the frictional loss of the pistons. The pistons are connected by a rod *q*, passing 55 through the stuffing box or boxes *i* and *j*. The rod *q* is provided with a coupling-pin *r*, with which the forked inner end of an operating hand-lever *h* is engaged. This hand-lever is pivoted to an arm *g* on the housing 60 *e*. By depressing the hand-lever *h*, so as to raise the pistons *k* and *l*, the upper piston forces the fluid above it into the air-chamber *f* and thence into the lift or discharge pipe *b*. When the pistons have reached their upper- 65 most positions and the power upon the hand-lever ceases, the pressure of the fluid column in the lift or discharge pipe acts to facilitate the return of the hand-lever. The pump shown in Fig. 2 is also provided with differential pistons *k* and *l*, which in this instance are both used as working pistons, the outer surfaces of both pistons being subjected to the pressure of the forcing fluid column by reason of the connecting-pipes *p*. The inner 70 end of the upper pressure-cylinder also communicates with the air-chamber *f* through an upper valve-casing *s*, also provided with a suction-valve *m* and pressure-valve *o* and having a suction-pipe *n* connected therewith. 75 The action of this pump is the same as that of the pump shown in Fig. 1, with the difference, however, that the delivery of fluid takes place at every stroke. The pistons are also subjected to the constantly-balancing pressure of the lift-column, whereby a considerable saving in the power for lifting the hand-lever is effected. 80

Having thus described my invention, the following is what I claim as new therein and 90 desire to secure by Letters Patent:

1. A hydraulic pump comprising a fluid-column cylinder having a discharge-pipe, the lower pressure-cylinder, the upper pressure-cylinder, the housing whereby the upper pressure-cylinder is supported on the lower pressure-cylinder, the lower and upper pipes whereby the lower and upper pressure-cylinders are connected with the fluid-column cylinder, the valve-casing, connecting the lower 95 pressure-cylinder with the fluid-column cylinder, having suction and pressure valves, a suction-pipe connected with the valve-casing, the pistons working in the lower and upper 100

- pressure-cylinders, the rod, connecting the pistons, having a coupling-pin and an operating hand-lever pivoted to the housing and engaging the coupling-pin for reciprocating the pistons, substantially as set forth.
2. A hydraulic pump comprising a fluid-column cylinder having a discharge-pipe, the lower pressure-cylinder, the upper pressure-cylinder of larger diameter than the lower pressure-cylinder, the housing whereby the upper pressure-cylinder is supported on the lower pressure-cylinder, the lower and upper pipes whereby the lower and upper pressure-cylinders are connected with the fluid-column cylinder, the valve-casing connecting the lower pressure-cylinder with the fluid-column cylinder, having suction and pressure valves, a suction-pipe connected with the valve-casing, the differential pistons working in the lower and upper pressure-cylinders, the rod, connecting the pistons, having a coupling-pin and an operating hand-lever pivoted to the housing and engaging the coupling-pin for reciprocating the pistons, substantially as set forth.
- 15
- 20
- 25

3. A hydraulic pump comprising a fluid-column cylinder having a discharge-pipe, the lower pressure-cylinder, the upper pressure-cylinder, the housing whereby the upper pressure-cylinder is supported on the lower pressure-cylinder, the lower and upper pipes whereby the lower and upper pressure-cylinders are connected with the fluid-column cylinder, the valve-casings connecting the lower and upper pressure-cylinders with the fluid-column cylinder, each having suction and pressure valves, suction-pipes connected with the valve-casings, the pistons working in the lower and upper pressure-cylinders, the rod, connecting the pistons, having a coupling-pin and an operating hand-lever pivoted to the housing and engaging the coupling-pin for reciprocating the pistons, substantially as set forth.

In witness whereof I have hereunto set my hand in presence of two witnesses.

WILHELM WAGNER.
